UNITED STATES PATENT OFFICE

FREDRIK W. HVOSLEF, OF KOHLER, WISCONSIN

RADIATOR CABINET

Application filed January 12, 1933. Serial No. 651,349.

My invention relates to improvements in radiator cabinets of the type used to enclose a heating radiator for protection and to render the installation more sightly.

5 Heating radiators are customarily formed of a number of separately cast sections joined together by nipples, thus practically any desired length of radiator may be formed by joining the required number of sections. It has heretofore been customary to form the radiator cabinet to fit and enclose the radiator, hence a large number of different sizes of cabinets are necessary to accommodate the many different lengths of radiators used in current practice.

10 It is an object of my invention to provide a radiator cabinet which is readily adaptable to radiators of varying lengths, thus reducing the number which must be kept in stock to meet the demands of the trade and simplifying the manufacture thereof.

15 It is a further object of my invention to provide a radiator cabinet which is practical and sightly, yet less expensive to manufacture than those now customarily used.

20 Still another object of my invention is to provide novel means for securing an ornamental grille in position at the top of the cabinet.

25 I attain these objects by the mechanism illustrated in the accompanying drawings, in which Figure 1 is a front elevation showing the cabinet enclosing a radiator; Fig. 2, a plan view of the radiator and cabinet; Fig. 3, a side elevation of the cabinet; Fig. 4, a sectional view along the lines 4-4 of Fig. 2; Fig. 5, a sectional plan view of an end section of the radiator showing the method of attaching the cabinet thereto; Fig. 6, a perspective view of the radiator and cabinet; Fig. 7, a front elevation of a modification of the cabinet; Fig. 8, a side sectional view along the lines 8-8 of Fig. 7; Fig. 9, a sectional plan view along the lines 9-9 of Fig. 7; and Fig. 10, a side sectional view along the lines 10-10 of Fig. 7.

30 Similar numerals refer to similar parts throughout the several views.

35 The radiator 1 has the sections thereof, or at least the end sections, formed with a

bead or extension 2 at the front and back of the section. The cabinet consists of four parts, the top 3, the back 4, and a pair of similarly formed end pieces 5. The cabinet is preferably formed of sheet metal, but may be made of any suitable material, it being necessary, however, that the end pieces 5 have sufficient elasticity or springiness to enable them to be opened somewhat for attachment to the radiator as hereinafter described. The end pieces are adapted to form, with the end section of the radiator, an enclosure, preferably rectangular in shape. Adjacent the end section of the radiator the sides of the end pieces 5 are formed with an inwardly extending flange 6. A second inwardly extending flange 8 is spaced from the flange 6 a sufficient distance to form therebetween a groove or gain adapted to receive the bead 2 of the radiator, as best shown in Fig. 5. A third inwardly extending flange 7 is provided with a perforation adapted to receive the hook rods or other connecting means 9. The inwardly extending flanges 7 and 8 may be formed, as shown in Fig. 5, by a channel iron secured to the sides of the end piece. The rods 9 are joined by the coil spring 10 which provides sufficient inward tension to hold the end piece 5 in firm contact with the radiator and the flanges 6 and 8 in engagement with the bead 2. It will be understood that in case the end piece 5 is formed of relatively stiff material so that its own elasticity will hold it firmly in engagement with the radiator, the rods 9 and the spring 10 may be dispensed with. The end pieces 5 may be readily attached to the radiator by springing them enough to allow the flanges 6 and 8 to be placed over the bead 2 of the radiator and may readily be detached by reversing the process.

35 After both of the end pieces 5 are positioned, the back 4 is attached to them by means of hooks 11 or in any other suitable manner.

40 It will be noted that the construction of the end pieces 5 remains the same regardless of the length of the radiator. The back 4 may overlap the end pieces 5 a considerable

extent without detracting from the appearance of the cabinet; therefore the same back is adaptable to several different sizes of radiators, it being necessary only that the 5 back be long enough to cover the space between the end pieces and not long enough to protrude beyond the end pieces.

The top 3 is provided with a pivoted closure 12 which may be raised to provide 10 access to the regulating valve 13 of the radiator which is concealed from view by the end piece 5.

It will be seen from the foregoing description that the only part of the cabinet which 15 must be of an exact size to correspond with the radiator is the top 3. This reduces the number of cabinets or parts which must be kept in stock and simplifies the problem of manufacture.

20 The exposed portion of the radiator is decorated to correspond or harmonize with the decoration of the cabinet, and the whole makes a pleasing and sightly installation.

Figures 7 to 10, inclusive, illustrate a 25 modification of the invention adapted for use where the radiator is partially enclosed in a recess 14 in the wall 15. In this case one extremity of the end pieces 5 is provided with the flanges 6 and 8, while the 30 opposite extremity terminates in the flange 16 adapted to abut the wall 15. The connecting means 9 is attached to the radiator in any suitable manner as by looping around one of the tubes thereof.

35 The top 3 is supported at the front by the end pieces 5 as usual and at the rear by brackets 17 attached to the wall 15. The brackets 17 preferably are formed with an extending baffle 18 designed to prevent heat 40 from escaping upwardly along the wall 15 and causing discoloration thereof.

The appearance of the cabinet, either of the above described forms, may be improved 45 by closing off the space between the radiator and the top of the cabinet, with an ornamental grille 19. Brackets 20 are attached to the grille 19 at each extremity thereof. The bracket 20 has a bent over portion 21 forming a shoulder adapted to rest on the 50 radiator 1 and a forwardly extending hook shaped portion 22 adapted to engage or hook over the front portion of the end piece 5. The grille 19 is thus held upright and in position by the engagement of the bracket 55 20 with the end pieces 5 and the radiator 1. The top 3 rests on the forwardly extending portion 22 and further serves to hold it in place.

It will be understood that the exact 60 constructions shown are illustrative only and that many variations may be made by those skilled in the art without departing from

the spirit of my invention. I do not, therefore, limit myself to the identical forms shown, but claim all modifications thereof which are within the spirit of my invention and the scope of the appended claims.

70 I claim:

1. A radiator cabinet comprising a pair of end pieces, means for attaching said end pieces to the radiator, a top adapted to rest upon said end pieces, a grille adapted to close the space between the radiator and said top, and means for attaching and supporting said grille, said means comprising a bracket having a shoulder adapted to rest on the radiator and a forwardly extending portion adapted to engage the aforesaid end pieces.

75 2. A cabinet for a radiator having beaded end sections comprising a pair of end pieces, means for attaching said end pieces to the radiator, said attaching means comprising a gain in said end piece adapted to receive the bead of the radiator, and means for holding said gain in juxtaposition to said bead, and a top adapted to fit and rest upon said end pieces.

80 3. A cabinet for a radiator having beaded end sections comprising a pair of end pieces, means for attaching said end pieces to the radiator, said attaching means comprising a gain in said end piece adapted to receive the bead of the radiator, and a top adapted to fit and rest upon said end pieces.

85 4. A cabinet for a radiator having beaded end sections comprising a pair of end pieces, means for attaching said end pieces to the radiator, said attaching means comprising a gain in said end piece adapted to receive the bead of the radiator, and means for holding said gain in juxtaposition to said bead, a 90 back, means for attaching said back to said end pieces, and a top adapted to fit and rest upon said end pieces.

95 5. A cabinet for a radiator having beaded end sections comprising a pair of end pieces, means for attaching said end pieces to the radiator, said attaching means comprising a gain in said end piece adapted to receive the bead of the radiator, a back, means for attaching said back to said end pieces, and a top adapted to fit and rest upon said end pieces.

100 6. In a cabinet for a radiator having end sections provided with one or more beads, the combination of an end piece and means 105 for attaching said end piece to the radiator, said attaching means comprising one or more gains located in said end piece and adapted to receive the bead of the radiator, and means for holding said gain in juxtaposition to said bead.

110 FREDRIK W. HVOSLEF.
